UNITED STATES PATENT OFFICE

WILLIAM K. EDWARDS, OF BIG SPRING, TEXAS

GRIP TESTER

Application filed March 10, 1928. Serial No. 260,755.

This invention relates to machines for testing the muscular strength of the arm and hand and of the type in which the insertion of a coin or check is necessary in order to render 5 the machine operative. The machine is provided as usual with means to register in pounds the gripping strength of the operator. A machine of the same general type is disclosed in U. S. Letters Patent 1,640,030, 10 issued to me on August 23, 1927 and the present invention is directed to certain improvements in the machine of said patent.

An important feature of the invention is found in a construction whereby upon the insertion of a coin of suitable denomination, and thereafter the application of force to the gripping members, the coin becomes an operative member of the machine, necessary to unlock the operative parts thereof. By thus 20 causing the coin to become an instrumental factor in the release of the moving parts of the machine, the mechanism is rendered positive, and the force of gravity is not depended upon in the performance of the unlocking 25 operation. The mechanism in question is, by reason of its positive action, incapable of being fraudulently operated by the insertion of objects therein, as is possible with a gravity operated machine. The foregoing, and other 30 important features of the invention, including improved combinations of elements and details of construction will be best understood from the following description, when considered in connection with the accompanying 35 drawings.

In the drawings which illustrate a preferred form of the invention:

Fig. 1 is a side elevation of the mechanism as disclosed by a vertical section through 40 the enclosing casing;

Fig. 2 is a sectional plan view;

Fig. 3 is a view similar to Fig. 2, but with the casing omitted, and the locking mechanism shown open as the machine is being operated;

Fig. 4 is a section on the line 4—4, Fig. 2, looking in the direction of the arrow; and

Fig. 5 is a section on the line 5—5, Fig. 2, looking in the direction of the arrow.

The mechanism of the machine is enclosed

in a casing 1 which in practice is provided with one or more removable panels, locked to the casing, but removable to obtain access to the mechanism. A front plate 4 of the casing is provided with two perforations 55 through which extend the inner ends of tubular members, 8, said ends of the members 8 also extending through perforations in the base plate 5^a of a strong metal frame 5, which latter sustains the mechanism within the casing. Clamping nuts 9 are in threaded engagement with the ends of the tubular members 8, and said members are provided, exteriorly of the plate 4, with annular enlargements or shoulders 8^a. By screwing the nuts 60 9 upon the threaded ends of the tubular members 8, accordingly, the several parts referred to, namely, tubular members 8 and frame 5, are clamped against the plate 4, rigidly holding said parts together.

The tubular members 8 are connected by a bar 10, forming a handle and a second handle 12, located to the rear of the bar 10 provided with two parallel forwardly extending rods 14, which are telescopically received and slide freely within the members 8, the rods 14 extending within the casing 1, and through apertures in a rigid metal plate 16. The inner ends of the rods 14 are provided with screw threads to receive nuts 17 which serve to clamp the plate 16 against shoulders formed near the inner extremities of the rods.

The inner end of the frame 5 is perforated to receive a rod 22 which extends forwardly, passing through a hole in the plate 16. Said rod is surrounded by a strong spiral spring 18, confined between the rear end portion of the frame and the plate 16 and so that rearward movement of said plate caused by gripping the handles 10 and 12 is resisted by the spring 18. A suitable registering device 44, comprising a dial having a pointer moving over a scale thereon which is calibrated to denote in pounds the amount of gripping pressure exerted on the handles, is provided as usual in machines of this class. The operation of the pointer on the dial to denote the amount of gripping force exerted is effected through an arm 40, adapted to be actuated upon engagement therewith of the upper portion of 100

the plate 16 as the latter is caused to move rearwardly against the force of the spring 18, and said arm is connected with mechanism as a segment and pinion as disclosed in the 5 aforesaid patent to cause the pointer to rotate about the dial.

The machine is normally locked against 10 operation by a lever 48 having a downwardly projecting stem 49 which has bearing in a nut 50 threaded in an aperture through a horizontal portion 5^b of the frame 5, the lever 48 being provided at its rear portion with a notch 51, adapted to engage the rear face of the plate 16 when the parts are in position 15 as shown in Fig. 2, thus obstructing the rearward movement of the plate, and preventing the operation of the machine. The locking engagement between the notch 51 and the plate 16 is interrupted through the instrumentality of a coin of suitable denomination, 20 as will be hereinafter more fully described.

A spring 60 extends from a fixed anchoring point 61, herein shown as a screw projecting from a bracket 62, clamped to the frame 5, 25 and has its opposite end connected with the rear portion of the lever 48, said spring normally acting to pull the rear end of said lever towards the bracket 62 to unlock the plate 16. The lever 48 is held against the 30 unlocking movement of the spring 60 by a leaf spring 27 which at one end is rigid with the bracket 62 while its free end extends transversely of the machine and in position to engage a notch 72 formed in a head 71 on the 35 lever 48. The head 71 is perforated to receive a rod 68 which extends therethrough and has its inner end beneath the outer end portion of the spring 27, and in position, when actuated through the instrumentality of 40 a coin, to push the spring away from the notch 72 and release the lever 48, permitting the spring 60 to turn said lever about the axis 49 and unlock the plate 16 whereby the machine is free to be operated.

The rod 68 is provided with a shoulder 68^a 45 between which and the rear face of the head 71 is a spiral spring 69, said spring surrounding the rod. The shoulder 68^a is part of a metal coin receiver 73, attached to 50 the rod 68 and movable with it, while the counterpart of the coin receiver 74 is rigid with the forwardly extending arm of the lever 48, and the coin receiving elements 73, 74 are provided with a coin slot 75, formed 55 partly in each. The coin receiving member 73 has at its rear end a downwardly extending vertically arranged abutment 55, and the plate 16 has secured thereto a bracket 56 having a horizontal laterally extending arm 57 60 which extends beneath the slot 75, and serves to support a coin.

The machine is provided with a coin chute 58 which extends diagonally through the front wall of the casing, its rear end terminating immediately above the slot 75, while 65

its front end is provided with a coin opening 59.

An arm 64 is fastened to one side of the frame 5 and extends upwardly in position to limit the lateral swinging movement of 70 the lever 48 under the influence of the spring 60.

A lug 78 extends upwardly from the head 71, and is provided with a perforation through which freely slides a rod 79, the rear end of the rod being threaded to receive one or more nuts 80 which act as abutments to engage the lug. The forward end of the rod is bent downwardly at 80^a and engages an aperture in a lug 81 projecting from the rear face of the plate 16. Said rod, upon rearward movement of the plate 16 when the handle 12 is released, under the influence of the spring 18, acts through the nut 80 and lug 78 to rotate the lever against the tension of the spring 60, until the leaf spring 27 snaps behind the shoulder 72, thus holding the lever 48 in position to lock the machine.

The rear end portion of the lever 48 is shown as provided with a slot 82, to receive 90 a pin upon a crank arm 83 which operates an odometer 84, for counting the number of operations of the machine.

In operation, upon the insertion of a coin of suitable denomination in the aperture 59, 95 the coin will travel by gravity down the coin chute 58 and thence into the slot 75 between the coin members 73, 74 and rest upon the projection 57. As thus positioned the coin forms a connector between an abutment 85, 100 formed in the rear portion of the projection 57, and a similar abutment 55, formed at the forward end of the coin slots 75 in the coin member 73. Pressure being now applied to the handle 12, the coin is forced rearwardly 105 and pushes the rod 68 through the aperture in the head 71, forcing the free end of the leaf spring 27 out of engagement with the notch 72, and permitting the spring 60 to swing the lever about its pivot 49 and removing the shoulder 51 laterally away from the plate 16, thus unlocking the machine. Continued pressure upon the handle 12 being 110 now exerted by the operator, the spring 18 is compressed to that degree which the operator's strength permits and the gripping force thus exerted is registered on the dial 44 by the pointer, which moves around the dial and indicates the pressure in pounds 115 thereon. After the plate 16 has been moved and the spring compressed to the limit of the operator's strength, upon release of the pressure the spring 18 will expand, forcing the plate rearwardly again, and the rod 79 by engagement of the nuts 80 thereon with the lug 78, rotating the lever 48 reversely 120 against the tension of the spring 60, until the spring 27 again snaps back of the notch 72, thus locking the lever 48 in the position 125 shown in Fig. 2, which also is the position 130

where the machine is locked against operation. The parts will remain in this position until another coin of the proper denomination is inserted in the machine and the operation as above described repeated.

Having thus described my invention, what I claim as new and desire to secure by Letters Patent is:

1. In a grip testing machine, a grip resisting spring, a handle for compressing said spring, a rocking lever for preventing movement of said handle, means for rotating said lever to release said handle, detent mechanism to prevent rotation of said lever and devices operated by pressure applied through an inserted coin for actuating said detent mechanism to release the lever.

2. A grip testing machine comprising a movable handle, a spring whose tension is exerted to resist movement of said handle, a lever pivoted to swing into and out of position to lock said handle against movement, a spring for moving said lever out of locking position, a detent for holding said lever in locking position against the tension of said spring, a coin supporting device movable with said handle, coin receiving members carried by said lever, and a rod arranged to be actuated by pressure transmitted through a coin for releasing said detent.

In testimony whereof I have hereunto set my hand this 3d day of March, A. D. 1928.

WILLIAM K. EDWARDS.
